DERRICK CONSTRUCTION.

Application filed December 21, 1925. Serial No. 78,646.

This invention relates to improvements in derrick construction, and is particularly directed to the general type of derrick structures usually employed in the drilling and operating of oil, gas and like wells.

More specifically, the present invention is directed to certain improvements in the construction of the type of panel derrick disclosed in my co-pending application, Serial No. 68,208, filed November 10, 1925, and has for an object to provide an improved method of constructing the several panels so as to permit a closer intermeshing of the several adjacent panels at the corners of the derrick and so as to provide more rigid corner posts or legs.

It is a further object to so construct the several panel sections of the derrick so that in the assembled derrick the girts and braces will be clamped between the adjacent leg members.

Various other objects and advantages will be more fully apparent from the following description of the accompanying drawings which form a part of this disclosure, and which illustrate a preferred form of the embodiment of the invention.

Of the drawings:

Fig. 1 is an elevation of a derrick of the general type to which the present invention is directed.

Fig. 2 is an enlarged plan section, partly broken, taken on line 2—2 of Fig. 1.

Fig. 3 is an elevation of a single panel section of the form utilized in two opposite sides of the derrick.

Fig. 4 is a similar elevation of a single panel section of the form utilized in the other two sides of the derrick.

Fig. 5 is an enlarged detailed section taken on line 5—5 of Fig. 1.

In the construction disclosed in my previous application, above identified, the several girts and sway braces of each panel section are secured to the respective angle-iron leg members by bolts or rivets having projecting heads, and in such a manner that when the adjacent sections are assembled with the angle-iron leg members of said sections in intermeshing relation, said angle-iron leg members clamp against the adjacent bolt or rivet heads.

In certain instances it has been found that it is more desirable to so construct the panel

sections that when assembled together in a derrick, the ends of the several girts and sway braces will be directly engaged by and be clamped rigidly between the two angle-iron leg members at each corner of the derrick, this being most effectively accomplished by securing the girts and braces to the respective leg members by bolts or rivets having countersunk heads.

In a derrick of this general type of construction, each of the four sides is formed of a plurality of panel sections secured together in vertical alignment with the several sections of the respective sides of suitable dimensions to produce a completed derrick gradually converging or tapering upwardly to the derrick top.

The panel sections A (see Fig. 4) of two opposite sides of the derrick are of relatively similar construction and the panel sections B (see Fig. 3) are also of relatively similar construction, but slightly different from the panel sections A; therefore it will suffice herein to describe in detail only one of each of the sections A and B.

Each panel section A comprises opposite angle-iron leg members *a* disposed vertically at slightly converging angles corresponding to the general taper of the completed derrick, lower and upper transverse marginal girts 2 and 3 (so-called because they form the lower and upper margins of the panel), an intermediate transverse girt 4, a lower pair of diagonal sway braces 5 and 6, and an upper pair of similar diagonal sway braces 7 and 8, there being also provided vertical reinforcing braces 9 if desired. These girts and braces may be formed of angle-iron and swaged at their opposite ends to bring both flanges thereof to parallel contact, thus providing securing ends of double thickness or they may be formed of flat or other shaped material. The opposite ends of the respective girts and braces are bored or punched to receive the securing bolts or rivets and are positioned to engage the inner faces of the adjacent flanges of the respective leg members *a*, said girts and braces being secured in place preferably by bolts and nuts with the bolt heads countersunk into the inner surfaces of the respective girts and braces and the associated nuts tightened against the outer faces of the respective leg members. (See particularly

Fig. 2.) These several bolts are designated by reference characters consisting of a suffix added to the numeral designating the respective parts they secure to the leg members, thus bolts 2^a secure the transverse marginal girt 2 to the lower ends of the leg members *a*, the bolts 3^a secure the transverse marginal girt 3 to the upper ends of said leg members, while the bolts 4^a, 5^a, 6^a, 7^a and 8^a secure the intermediate girt and respective diagonal sway braces to said leg members.

Each panel section B comprises opposite angle-iron leg members *b*, lower and upper transverse marginal girts 10 and 11, an intermediate transverse girt 12, a lower pair of diagonal sway braces 13 and 14, an upper pair of diagonal sway braces 15 and 16, and vertical reinforcing braces 17, if desired.

All of these girts and braces are of the same construction as those of the panel section A. However, their ends are secured by bolts and nuts to the outer faces of the adjacent flanges of the respective leg members *b*, instead of to the inner faces as are the girts and braces of the sections A, the heads of said bolts being countersunk into the outer surfaces of the respective girts and braces and the associated nuts tightened against the inner faces of the respective leg members. (See Fig. 2.) Bolts 10^a secure the lower marginal girt 10 to the lower ends of the respective leg members *b*, bolts 11^a secure the upper marginal girt 11 to the upper ends of the respective leg members *b*, while bolts 12^a, 13^a, 14^a, 15^a and 16^a secure the intermediate girt 12 and the respective diagonal sway braces to the leg members *b*.

With particular reference to Figs. 1 and 5, it will be noted that in the completed derrick the several panel sections comprising each side of the derrick are vertically aligned one upon the other with the lower marginal girt of each section engaging the upper marginal girt of the next lower section and that the co-engaging marginal girts are secured together by bolts 18. As shown in Fig. 5, the adjacent A and B sections overlap each other by one-half their respective heights, thus bringing the joints 19 between the vertically adjacent A sections in regular staggered relation to the joints 20 between the vertically adjacent B sections.

Referring now more particularly to Fig. 2 of the drawings, it will be noted that the panel sections A are assembled with the panel sections B so that the angle-iron leg members *a* have an intermeshing or overlapping engagement with the angle-iron leg members *b* of the panel sections B, and that the inner flat surfaces of the ends of respective girts and braces of the sections A engage the outer faces of the leg members *b* of the sections B, while the outer flat surfaces of the ends of the respective girts and

braces of the sections B engage the inner faces of the leg members *a* of the sections A. Thus when the leg members are secured together, as will be explained, the ends of the girts and braces will be rigidly clamped between the companion leg members at each corner of the derrick. This distinguishes from the construction disclosed in my previous application in which the leg members clamped against both heads and not against the ends of the girts and braces, and is of material importance in preventing a shearing of the bolts by reason of excessive vibration and in producing a more rigid and durable construction.

With the panel sections thus assembled, the nested leg members are secured together at intervals by bolts A' and B', each of said bolts extending through apertures 21 in the flanges of both leg members *a* and *b* of each corner post of the derrick.

From the above it will be seen that the present invention provides a derrick construction having corner legs each consisting of two intermeshing angle-iron leg members, and connected braces and girts arranged to be rigidly clamped between and secured to said leg members so as to relieve the securing bolts of detrimental vibratory influences and providing a very rigid and durable construction.

While the specific embodiment herein illustrated and described is fully capable of fulfilling the objects primarily stated it is to be understood that I do not wish to restrict the invention in this regard, for it is susceptible of embodiment in various other forms, all coming within the scope of the claims which follow.

I claim as my invention:

1. In a derrick of the nature disclosed, the combination of: relatively spaced corner legs each comprising a double string of longitudinally aligned leg members; transverse girts and braces forming the respective sides of the derrick and having their opposite ends disposed between the adjacent companion leg members; and means for clamping said girts and braces between said leg members.

2. In a derrick of the nature disclosed, the combination of: relatively spaced corner legs each comprising a double string of longitudinally aligned angle-iron leg members, one string nested within the other with their flanges in parallel relationship with the adjacent sides of the derrick; transverse girts and braces forming the respective sides of the derrick and having their opposite ends disposed between the flanges of the adjacent leg members; and means for drawing said leg members together to clamp said girts and braces.

3. In a derrick of the nature disclosed, the combination of: relatively spaced corner

- legs each comprising a double string of longitudinally aligned leg members; transverse girts and braces forming the respective sides of the derrick and having their 5 opposite ends disposed between and in contact with the adjacent companion leg members and secured to one of said leg members; and means for drawing said leg members together to clamp said girts and braces.
- 10 4. In a derrick of the nature disclosed, the combination of: relatively spaced corner legs each comprising a double string of longitudinally aligned angle-iron leg members, one string nested within the other with 15 their flanges in parallel relationship with the adjacent sides of the derrick; transverse girts and braces forming the respective sides of the derrick and having their opposite ends disposed between and in contact with the 20 flanges of the adjacent leg members and secured to the flange of one of said leg members; and means for drawing said leg members together to clamp said girts and braces.
- 25 5. In a derrick of the nature disclosed, the combination of: relatively spaced corner legs each comprising a double string of longitudinally aligned angle-iron leg members, one string nested within the other with their 30 flanges in parallel relationship with the adjacent sides of the derrick; transverse girts and braces forming the respective sides of the derrick and having their opposite ends disposed between the flanges of the adjacent 35 leg members, the girts and braces of two opposite sides of the derrick being secured to the outer faces of the adjacent flanges of the
- inner leg members and the girts and braces of the two other sides of the derrick being secured to the inner faces of the adjacent 40 flanges of the outer leg members; and means engaging through both flanges of the several leg members for drawing them together to clamp the girts and braces.
6. In a derrick of the nature disclosed, the 45 combination of: relatively spaced corner legs each comprising a double string of longitudinally aligned leg members; transverse girts and braces forming the respective sides of the derrick and having their opposite 50 ends disposed between and in contact with the adjacent companion leg members, said girts and braces being secured at each end to one of said leg members by a countersunk bolt; and means for drawing said leg 55 members together to rigidly clamp said girts and braces.
7. A derrick having double leg members; girts having their ends disposed between said leg members and secured to one end 60 thereof; and means for drawing said leg members together to rigidly clamp said girts.
8. A derrick having double leg members; girts having their ends disposed between 65 said leg members and secured to one end thereof by countersunk bolts so as to permit the companion leg member to contact said girts; and means for drawing said leg members together to rigidly clamp said girts. 70

In testimony whereof, I have hereunto set my hand at Los Angeles, California, this 10th day of December, 1925.

BURTON BLACK.
